UNITED STATES PATENT OFFICE.

WILLIAM FINKELSTEIN, OF PHILADELPHIA, PENNSYLVANIA.

HAND-BAG STRUCTURE.

Application filed January 11, 1927. Serial No. 169,451.

This invention relates to frames for traveling bags, suit cases and the like and has for its purpose the provision of a new and improved frame structure or attachments 5 therefor whereby the construction of the hinge joint will be improved and the assembly of the bag proper facilitated.

In the present practice of making traveling bags U shaped hinges are generally used. 10 Examples of frames of this general form are shown in the U. S. Patents #1,124,467 and #1,601,047 granted to Lange and Shwayder respectively. In the course of assembling 15 the bag two practices are followed in reference to the covering of the frame and hinge depending on whether the bag is hand sewed or machine sewed.

In hand sewed or "English" bags, the frame is first assembled. (These frames are 20 of such a form that the hinge portion is offset from the frame proper. See Figure 4 of Lange cited.) The frame is then covered with leather. The bag is then sewed on to the frame.

25 In machine sewed bags, each frame section is first covered. Here also two courses are followed depending on whether the bag is to be an imitation "English" or just an ordinary machine sewed bag.

30 If an imitation "English", then a large rivet is inserted in the hole provided at each end of one of the frame sections. In covering that section care must be taken to cover the portion around the rivet. A hole must 35 be made in the leather so that the rivet will extend through the same. The bag portion is now sewed on to the frame section. Finally the frame sections are joined together, the rivet aforesaid acting as the hinge point.

40 If the bag is an ordinary machine sewed bag, each frame section is first covered. In covering that portion of the frame which will form the outer or exposed hinge point, care is taken not to cover the hole which is 45 to receive the hinge rivet. The bag portion is attached to the frame portion. The two sections are now riveted together. The outside of the hinge portion is now covered with an ornamental cap such as shown at 12 in 50 Figure 3 of Shwayder cited. This cap serves to hide the rough edges of the leather, the uncovered end of the frame, etc.

The applicant has devised a frame structure having hinges adaptable for all types 55 of bags and which could be more easily assembled than those in the previous art.

The following summary of some of the purposes of the applicant is given to more clearly bring out the present invention:

(1) To produce a frame structure whereby the hinge portion may be easily covered. 60 (2) To produce a frame structure whereby the assembly of the frame at the hinge portion will be facilitated.

(3) To produce a frame structure whereby the hinge structure will be standard no matter what type of bag is to be made. 65

(4) To produce a frame structure and so improve the hinge portion as to give a finer appearance and finish to all types of 70 bags.

(5) To produce a frame structure and so improve the hinge portion that extraneous ornaments covering rough ends will not be necessary thereby saving both time and 75 labor.

The above and other objects will become clearer from the following specification and drawings.

In the drawings Figure 1 is an end view 80 of one of the frame ends of the frame section which will form the outer portion of the hinge.

Figure 2 is a section taken on the line 2—2 of Figure 1. 85

Figure 3 is an end view of one of the frame ends of the frame section which will form the inner portion of the hinge.

Figure 4 is a section taken on line 4—4 of Figure 3. 90

Figure 5 is a front view of the assembled frame, parts being broken away.

Figure 6 is an end view of one of the frame ends of another form frame section which will form the outer portion of the 95 hinge.

Figure 7 is a front view of an attachment for the same.

Figure 8 is a section on line 8—8 of Figure 9. 100

Figure 9 is an end view of one of the ends of the frame section which is made by combining the disclosure in Figures 6 and 7, which said section will form the outer portion of the hinge.

Figure 10 is a top view of the split rivet and cap used in this invention but which in itself is old in the art.

Figure 11 is a section through line 11—11 of Figure 10. 110

Figure 12 is a view of the rivet shown in Figures 10 and 11.

Figure 13 is an end view of one of the ends of still another form of a frame section which will form the outer portion of the hinge.

5 Figure 14 is a detail of one of the elements shown in Figure 13.

Fig. 15 is a section on the line 15—15 of Fig. 13.

Referring in greater detail to the disclosure in the drawings, reference numeral 1 refers to one of the ends of the frame section which will form the outer portion of the hinge, the said part having an excrescence 2 forming a recess 3 which receives the cap 4 of the rivet portion 5.

Reference numeral 7 denotes one of the ends of the frame section which will form the inner portion of the hinge, the said part having a hole 6' which is adapted to register with the hole 6 in the frame section 1. The section 7 has a burr 8, the function of the burr being to serve as a guide and to insure the registry of the holes 6 and 6' in the frame sections 1 and 7.

25 In assembling a bag using the frame above described the cap 4 is placed in the recess 3 so that the open part of the cap faces the hole 6 in the frame section 1. The frame sections are then covered with leather.

30 If the bag is to be hand sewed the frame sections are immediately assembled in the following manner:

The frame section 7 is placed upon the frame section 1 in such a manner that the burr 8 registers with the hole portion 6 in the frame 1. The rivet 9 is then driven through the hole 6' in the frame 7 and binds the two frame sections together as shown in Figure 5.

40 If the bag is to be machine sewed, the frame sections are first covered in the manner outlined above. The bag is then attached to the frame sections in the manner well known in the art. The frame sections are then joined together as outlined above.

Reference numeral 10 denotes one of the ends of another modification of one of the frame sections which will form the outside of the hinge. This has the holes 11 thereon which register with the holes 11' in the part 50 12. The portion 12 has an excrescence 2' thereon which forms the outer casing of the hole cavity 3', the said portions 2' and 3' having the same functions as the portions 2 and 3 respectively. The frame end 10 has an excrescence 17 therein. This obviates the use of the cap 4, since the portion 17 serves exactly the same purpose as the excrescence in the cap 4 which serves to separate and 60 bend over the prongs of the rivet 9. The concomitant frame section used in conjunction with this type is similar in every respect to the frame section 7 and for that reason will not now be described.

65 In assembling the type of frame design-

nated by numeral 10, the cap 4 is placed between the two rivet holes 11 so that it fits into the cavity 3' in the portion 12. The portion 12 is then riveted or otherwise attached to the portion 10. This may of course be done at the time the frame is made at the factory or at the place of assembly of the bags. From this point onward the procedure in assembly is the same as that outlined in reference to frame sections 1 and 7. 75

Reference numeral 13 refers to still another modification of a frame section which may be used instead of the frame sections 1 or 10.

This differs from frame section 1 in having a rounded end 14' instead of the square end 14 and in having the protective and reinforcing plate 15. This plate has a square end 15 thus giving the frame the appearance of an "English" frame. 80

The plate 15 is attached to the frame portion 13 by a rivet through the holes 16 and 16' in the portions 13 and 15 respectively. The cap 4 fits into the recess 3'' formed by the excrescence 2'' as is obvious from the drawings. 85

In assembling the frame section 13, the cap 4 is placed in the recess 3''. The cap 15 is then riveted on the section 13.

The protective cap 15 in this case serves 95 two purposes:

First, it gives the frame the appearance of an "English" frame.

Secondly, it removes any possibility of a mark being left on the leather covering 100 by the cap 4 as a result of the reaction when the two frame sections are riveted together.

This second rôle is also played by the frame portion 15' of the frame 10.

It is obvious, of course, that a plate may 105 also be used in connection with frame 1 for purposes similar to those which impel the use of plate 15.

I am aware that many modifications and obvious changes of the above disclosure may 110 be made still embodying my inventive thought and for that reason the above disclosure has been made by the way of illustration only and not by the way of limitation. 115

Having disclosed my invention what I claim as new is:

1. In a frame section for hand-bags, traveling bags, suit cases or the like, means for forming the female member of a hinge carried by the said frame section, the said means consisting of an excrescence situated at the hinge point of the said frame section. 120

2. In a frame section for hand-bags, traveling bags, suit cases or the like, means for forming the female member of a hinge carried by the said frame section, the said means consisting of an excrescence situated at the hinge point of the said frame section, a depression in the said frame sections at 130

the said hinge point formed by the said excrescence, an inner bounding wall for the said depression formed by the said wall of the said excrescence, and a plate carried by 5 the said frame section at the said hinge point, the said plate forming a rear wall for the said depression.

3. In a frame section for hand-bags, traveling bags, suit cases or the like, means 10 for forming the female member of a hinge carried by the said frame section, the said means consisting of an excrescence situated at the hinge point of the said frame section, a depression in the said frame section at 15 the hinge point formed by the said excrescence, an inner bounding wall for the said depression formed by the walls of the said excrescence, means for forming rear wall for the said depression, the said means consisting of a plate carried by said frame section at its hinge point and a retaining element carried in the said depression of the frame section.

4. In a frame for hand-bags, traveling bags, 25 suit cases and the like composed of a plurality of sections, means for forming a hinge carried by the said frame sections, the said means consisting of a female member carried by one of the frame sections and a male member carried by another of the said frame sections; the said female member consisting of an excrescence carried by the said female frame section at its hinge point, a depression in the said frame section formed 30 by the said excrescence, an inner bounding wall for the said depression formed by the wall of the said excrescence, a hole in the said wall of the said excrescence, the said hole adapted to permit the passage of a retaining means, and means for forming the rear wall for the said depression, the said means consisting of a plate carried by the said frame section at its hinge point; the said male member consisting of retaining 35 means carried by the said male frame section; the said retaining means being adapted to register with the said hole in the said excrescence and extend therethrough into the said female members and interlock with the 40 said female member.

5. A frame for hand-bags, travelling bags, suit cases and the like, the said frame being composed of a plurality of sections, one of the said sections having an excrescence on 45 each of the ends thereof, the inner part of said excrescence forming a cavity in the said frame section, the outer part of said excrescence forming a protective wall for 50 said cavity, a retaining element in cavity, a hole in said excrescence adapted to register with an opening in the said retaining element and to permit the passage of retaining means; the other sections having burrs on 55 each of the ends thereof, the said burrs adapted to register with each of the holes

in the excrescence on the first said section, holes also adapted to register with the said holes in the first said section, retaining means binding the said sections together, the said binding means extending through the 70 aforesaid holes and interlocking with the retaining element in the said excrescences.

6. A frame for hand-bags, travelling bags, suit cases and the like, the said frame being composed of a plurality of sections, 75 one of the said sections having an excrescence on each of the ends thereof, the inner part of said excrescence forming a cavity in the said frame section, the outer part of said excrescence forming a protective wall for 80 said cavity, a retaining element in cavity, a hole in said excrescence adapted to register with an opening in the said retaining element and to permit the passage of said retaining means, a plate attachable to and 85 detachable from each of the ends of the said section, the said plate forming a rear wall for said cavity; the other sections having burrs on each of the ends thereof, the said burrs adapted to register with each of the 90 holes in the excrescences on the first said section, holes also adapted to register with the said holes in the first said section, retaining means binding the said sections together, the said binding means extending through the aforesaid holes and interlocking with the retaining element in the said excrescences.

7. A frame for hand-bags, travelling bags, suit cases and the like, the said frame being 100 composed of a plurality of sections, one of the said sections having an excrescence on each of the ends thereof, the inner part of said excrescence forming a cavity in the said frame section, the outer part of said excrescence forming a protective wall for said cavity, a retaining element in said cavity, a hole in said excrescence adapted to register with an opening in the said retaining element and to permit the passage of said retaining means, a plate attachable to and 105 detachable from each of the ends of the said section, the said plate forming a rear wall for said cavity, the other sections having burrs on each of the ends thereof, the said burrs adapted to register with each of the 110 holes in the excrescences on the first said section, holes also adapted to register with the said holes in the first said section, split rivets binding the said sections together, the said split rivets extending through the aforesaid holes and interlocking with the retaining element in the said excrescences.

8. In a frame-section for hand-bags, travelling-bags, suit-cases or the like, means 115 for forming the female members of hinges carried by the said frame-section, the said means consisting of excrescences situated at the hinge-points of the said frame-section.

9. In a frame-section for hand-bags, trav-

elling-bags, suit-cases or the like, means for forming the female members of hinges carried by the said frame-section, the said means consisting of excrescences situated at the hinge-points of the said frame-section, depressions at the said hinge-points formed by each of the said excrescences, an inner bounding wall for each of the said depressions formed by the walls of the said excrescences and means carried by the said frame-section at the said hinge-points, the said means forming a rear wall for each of the said depressions.

10. In a frame-section for hand-bags, travelling-bags, suit-cases and the like, means for forming the female members of hinges carried by the said frame section, the said means consisting of excrescences situated at the hinge-points of the said frame-section, 15 depressions in the said frame-section at the said hinge-points formed by the said excrescences, an inner bounding wall for each of the said depressions formed by the said walls of each of the said excrescences and a 20 plate carried by the said frame-sections at each of the said hinge-points, each of the said plates forming a rear wall for each of the said depressions.

11. In a frame-section for hand-bags, 30 travelling-bags, suit-cases and the like, means for forming the female members of hinges carried by the said frame-section, the said means consisting of excrescences situated at the hinge-points of the said frame-section, 35 depressions in the said frame-section at the said hinge-points formed by the said excrescences, an inner bounding wall for each of the said depressions formed by the walls of each of the said excrescences, means for 40 forming rear walls for each of the said depressions, the said means consisting of a plate carried by the said frame-section at each of the said hinge-points and a retaining element carried in each of the said depressions of the said frame-section.

12. In a frame-section for hand-bags, travelling-bags, suit cases and the like, means for forming the female members of hinges carried by the said frame-section, the said 50 means consisting of excrescences situated at the hinge-points of the said frame-section, depressions formed by the said excrescences, an inner bounding wall for each of the said depressions formed by the walls of each of the said excrescences, means carried by the 55 said frame-section at each of its hinge-points for forming the rear wall of each of the said depressions and a retaining element carried in each of the said depressions of the said 60 frame-section.

13. In a frame for hand-bags, travelling-bags, suit-cases and the like composed of a plurality of sections, means for forming hinges carried by the said frame-sections, the said means consisting of female members 65 carried by one of the said frame-sections and male members carried by another of the said frame sections; each of the said female members consisting of an excrescence carried by the said female frame-section at 70 its hinge-points, depressions formed by the said excrescences, an inner bounding wall for each of the said depressions formed by the walls of each of the said excrescences, a hole formed in each of the said inner bounding walls of each of the said excrescences adapted to permit the passage of retaining 75 means, means carried by the said female frame-section at each of its hinge-points for forming the rear wall of each of the said depressions; each of the said male members consisting of retaining means carried by the said male frame-section, each of the said retaining means registering with each 80 of the said holes in each of the said excrescences and extending therethrough into each of the said female members and interlocking 85 with each of the said female members.

14. In a frame for hand-bags, travelling-bags, suit-cases and the like composed of a 90 plurality of sections, means for forming hinges carried by the said frame-sections, the said means consisting of female members carried by one of the said frame-sections and male members carried by another of the 95 said frame-sections; each of the said female members consisting of an excrescence carried by the said female frame-section at each of its hinge-points, depressions in the said frame section formed by each of the said excrescences, an inner bounding wall for each of the 100 said depressions formed by the walls of each of the said excrescences, a hole formed in each of the said inner bounding walls of each of the said excrescences, the said hole 105 adapted to permit the passage of retaining means, and means for forming the rear wall for each of the said depressions, the said means consisting of a plate carried by the said female section at each of its hinge-points; each of the said male members consisting of retaining means carried by the said male frame-section, each of the said retaining means registering with each of the said 110 holes in each of the said excrescences and extending therethrough into each of the said female members and interlocking with each of the said female members.

In witness whereof I affix my signature.

WILLIAM FINKELSTEIN.
